(57) **CLAIM**

The ornamental design for an autograph board, as shown and described.

DESCRIPTION

FIG. 1 is a front perspective view of the autograph board showing my new design with a penholder clip shown in broken lines;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof (the left side comprising a mirror view of the right side elevational view). In the drawings, the broken lines represent environmental structure forming no part of the claim.
